PORTABLE GOLF GAME TARGET

Walter Zawacki, 3927 Porpoise Drive SE.,
St. Petersburg, Fla. 33705

Filed May 24, 1972, Ser. No. 256,634

Term of patent 14 years

Int. Cl. D21—02

U.S. Cl. D34—5 NN

FIG. 1

FIG. 2

FIG. 3

FIG. 4

FIG. 5

FIG. 6

FIG. 1 is a perspective view of a portable golf game target showing my new design;

FIG. 2 is a side elevational view of the portable golf game target shown in FIG. 1;

FIG. 3 is a top plan view of the portable golf game target shown in FIG. 1;

FIG. 4 is a bottom view of the portable golf game target shown in FIG. 1;

FIG. 5 is a rear elevational view of the portable golf game target shown in FIG. 1; and

FIG. 6 is a front elevational view of the portable golf game target shown in FIG. 1.

I claim:

The ornamental design for a portable golf game target, as shown and described.
